UNITED STATES PATENT OFFICE.

ALFRED H. HUMPHREY, OF NEW YORK, N. Y., ASSIGNOR TO GENERAL GAS LIGHT COMPANY, OF KALAMAZOO, MICHIGAN.

GAS-LAMP.

1,082,955.

Specification of Letters Patent.

Patented Dec. 30, 1913.

Application filed October 16, 1913. Serial No. 795,468.

To all whom it may concern:

Be it known that I, ALFRED H. HUMPHREY, citizen of the United States, residing at New York city, New York, have invented 5 certain new and useful Improvements in Gas-Lamps, of which the following is a specification.

This invention relates to improvements in gas lamps.

10 My invention relates particularly to improvements in gas lamps of the indirect type, or semi-indirect type, as they are sometimes called, that is, lamps in which the light is directed upwardly.

15 The main objects of this invention are: First, to provide an improved gas lamp of the indirect type. Second, to provide an improved gas lamp of the indirect type in which the parts of the lamp are so arranged 20 that the lamp is practically shadowless. Third, to provide an improved gas lamp of the indirect type in which the parts are so arranged as to secure the desired supply of fresh air to the mixing tube and to the burn-

25 ers at the point of combustion and at the same time, one in which the burner is protected from drafts or air currents, and the products of combustion escape without unduly heating any portion of the lamp or interfering with the fresh air supply to the burner. Fourth, to provide an improved 30 gas lamp of the indirect type which is very easily cared for, that is, one in which the parts are fully accessible for cleaning and 35 the mantle and burner parts are fully accessible for adjustment and renewal as desired.

Further objects, and objects relating to structural details, will definitely appear from the detailed description to follow.

40 I accomplish the objects of my invention by the devices and means described in the following specification. The invention is clearly defined and pointed out in the claims.

A structure which is a preferred embodiment 45 of my invention is clearly illustrated in the accompanying drawing forming a part of this specification, in which:

Figure I is a top perspective view of my improved gas lamp, the globe being omitted. 50 Fig. II is a detail vertical central section on a line corresponding to line 2-2 of Fig. III. Fig. III is a horizontal section on a line corresponding to line 3-3 of Fig. II. Fig. IV is an elevation view, the globe 55 and casing member being shown in vertical

section, the radiation of the light being indicated in conventional form.

In the drawing similar reference characters refer to similar parts throughout the several views, and the sectional views are 60 taken looking in the direction of the little arrows at the ends of the section lines.

Referring to the drawing, the supply pipe 1 is adapted as a support for the lamp. The burner is provided with a supply pipe 65 coupling 2 having a laterally projecting delivery arm 3. The burner is also provided with a horizontally disposed mixing tube arm 4, the mixing tube arm being below the coupling delivery arm 3. The burner tip 70 member 5 is disposed below the mixing tube member and provided with radially disposed burner arms 6 having inverted tips 7 thereon. The valve casing 8 is mounted upon the delivery arm 3 by means of the screw 9 75 having a longitudinal passage therein communicating with the valve casing. The valve 10 is provided with an operating lever 11.

The details of the operating connections 80 for the lever to the valve form no part of my present invention, therefore they are not further described herein. It is obvious that any suitable operating mechanism may be used in this relation.

85 The valve casing 8 is provided with a delivery nozzle 12 delivering to the mixing tube 13 which is telescoped into the mixing tube arm 4, the outer end of the tube being engaged upon the nipple 15 of the valve casing. The mixing tube is thus retained in position in the mixing tube arm of the valve casing and is freely removable when the valve casing is removed. A shield 16 is provided for the air inlets 17 of the mixing tube, 90 the shield being bell-shaped and mounted on the mixing tube with its open end directed outwardly. The pilot burner tube 14 is carried by the arm 3. The valve 18 coacts with the inner end of the mixing tube, it being 100 threaded into the inner end of the mixing tube arm 4. See Fig. II.

The casing member 19 is flared upwardly and open at the top and bottom, it being shaped quite like an inverted lamp shade. 105 The casing member is supported by arms 20 projecting from the burner arms 5 and secured to the lower end of the casing member by the screws 21. The arms 20 are in the form of straps of metal having down- 110

turned portions at their outer ends engaged by the screws 21 and upturned portions at their inner ends secured to the burner arms 5 by the screws 22. The casing member is supported with its upper edge in the plane or approximately in the plane of the mixing tube, and its lower end or mouth in the plane of the burner tips, the ends of the tips being slightly below the lower edge of the casing member, as clearly appears from the drawing. The mantles 23 are supported from the burner tips, the mantles being below the casing. The casing member is supported by the straps 20 in a spaced relation to all of the burners, permitting the radiation of light from the burners therebetween and the reflection of light from the inner surface of the casing. The walls of the casing shown are all in curved lines in cross section and this is the preferred form. The top of the casing member 19 is of such diameter that its outer edge lies well beyond the outer end of the valve casing 8. The casing is provided with an opening 24 for the valve operating chain or cord not shown.

The globe 25 is open at its upper end and it is supported with its upper edge in approximately the plane of the lower end of the casing member and so as to inclose the mantles 23. The globe is supported by the ring 26 suspended from the casing by the links 27. The diameter of the globe is considerably greater than the diameter of the lower end of the casing member so that there is a substantial space between the upper edge of the globe and the wall of the casing. This permits radiation of light from the mantles between the upper edge of the globe and the casing member, and also its reflection from the inner side of the globe between the globe and casing.

With the casing member supported in the relation described to the burner, the radiation of light from the burners is permitted through the top of the casing and also from below the same, and also reflected light from the inner surfaces of the casing and globe. By this arrangement, I secure a lamp of the indirect type which is shadowless, the direct and the reflected rays so crossing that the light is distributed with substantial uniformity on the ceiling or surface above the lamp without shadows from any of the lamp parts. The burners are well protected by the casing and the globe from currents and drafts of air, and the burner parts are covered from view from below. At the same time, the lamp being so open, free radiation is permitted so that none of its parts become unduly heated. A free supply of air to the mixing tube and also to the burners at the point of combustion is secured uncontaminated by the products of combustion passing from the burner.

By this arrangement of parts I secure a

lamp of the indirect type of high efficiency and one which is simple and economical in structure and easily cared for; also, the lamp is attractive and ornamental in appearance.

Having thus described my invention, what I claim as new and desire to secure by Letters Patent is:

1. The combination with the supply pipe, of an inverted burner provided with a pipe coupling having a laterally projecting delivery arm and a horizontally disposed mixing tube arm; a mixing tube projecting into said mixing tube arm; a valve casing mounted on the end of said delivery arm and provided with a nozzle delivering to said mixing tube, whereby the valve casing and the air inlet of the mixing tube are out of the path of the products of combustion; a casing member open at its top and bottom, said casing member being shaped like an inverted lamp shade; supporting arms for said casing member projecting from said burner, said casing member being entirely supported from said supporting arms with its upper edge substantially in the plane of said mixing tube arm and beyond the outer end thereof, the lower end of said casing member being in approximately the plane of the burner tip, there being a substantial space between all parts of the burner and the casing; and a globe open at its upper end suspended from said casing member, with its upper edge in approximately the plane of the lower end of the casing member, the diameter of the upper end of the globe being substantially greater than the diameter of the lower end of the casing member so that there is a substantial space between the globe and casing above, whereby light may radiate from the burner through the casing and also between the globe and the casing and light may also be reflected from the inside of the casing and from the inside of the globe through the casing and between the globe and casing.

2. The combination with the supply pipe, of a burner provided with a pipe coupling having a laterally projecting delivery arm, a mixing tube arm disposed horizontally below said delivery arm, a mixing tube projecting into said mixing tube arm; a valve casing mounted on the end of said delivery arm and provided with a nozzle delivering to said mixing tube, whereby the valve casing and the air inlet of the mixing tube are out of the path of the products of combustion; an upwardly flaring casing member open at its top and bottom; supporting arms for said casing member projecting from said burner, and secured to said casing at the bottom thereof, the lower end of said casing member being in approximately the plane of the burner tips, there being a space between all parts of the burner and the casing; mantles carried by the tips support-

ed below the lower end of the casing; and a globe open at its upper end suspended from said casing.

3. The combination with the supply pipe, 5 of an inverted burner provided with a pipe coupling having a laterally projecting delivery arm and a horizontally disposed mixing tube arm; a mixing tube projecting into said mixing tube arm; a valve casing mounted 10 on the end of said delivery arm and provided with a nozzle delivering to said mixing tube, whereby the valve casing and the air inlet of the mixing tube are out of the path of the products of combustion; an upwardly flaring casing member open at its 15 top and bottom; supporting arms for said casing member projecting from said burner, the lower end of said casing member being in approximately the plane of the burner tip, 20 there being also a space between all parts of the burner tip, there being a space between all parts of the burner and the casing permitting the radiation of light from the burner therebetween and reflected from the 25 inside of the casing; and a globe open at its upper end suspended from said casing.

4. The combination with the supply pipe, 30 of an inverted burner provided with a pipe coupling; an upwardly flaring casing member open at its top and bottom; supporting arms for said casing member projecting from said burner, said casing member being supported with its lower edge in approximately the plane of the burner tip, there being 35 a substantial space between all parts of the burner and the casing permitting the radiation of light from the burner therebetween and the reflection of light from the inside of the casing; and a globe open at

its upper end, suspended from said casing 40 member, with its upper edge approximately in the plane of the lower end of the casing member, the diameter of the upper end of the globe being substantially greater than the diameter of the lower end of the casing 45 member so that there is a substantial space between the globe and casing above through which light may radiate from the burner and may also be reflected from the inside of the globe. 50

5. The combination with the supply pipe, 55 of a burner provided with a coupling; a horizontally disposed mixing tube; a valve casing connected to said coupling and provided with a nozzle delivering to said mixing tube, said valve casing and the air inlets of the mixing tube being disposed out of the path of the products of combustion; an upwardly flaring casing member open at 60 its top and bottom; supporting arms for said casing member projecting from said burner, and secured to said casing at the bottom thereof, the lower end of said casing member being in approximately the plane of the burner tips, there being a space between all parts of the burner and the casing; 65 mantles carried by the tips supported below the lower end of the casing; and a globe open at its upper end suspended from said casing. 70

In witness whereof, I have hereunto set my hand and seal in the presence of two witnesses.

ALFRED H. HUMPHREY. [L.S.]
